[57] CLAIM

The ornamental design for an electrooptic display for
blood pressure device, as shown and described.

DESCRIPTION

FIG. 1 is a top plan view of an electrooptic display for
blood pressure device showing my new design in an
unenergized condition.

FIG. 2 is a front elevational view thereof;

FIG. 3 is a right side elevation view thereof, the left side
being a substantially mirror image thereof,

FIG. 4 is a bottom plan view thereof; and

FIG. 5 is a top plan view thereof, in a representative
energized condition displaying blood pressure as
120/80 and displaying a "cuff deflate" symbol.
